(57) **CLAIM**

The ornamental design for a baking basket, as shown and described.

DESCRIPTION

FIG. 1 is a perspective view of the baking basket showing my new design in a closed configuration;

FIG. 2 is another perspective view of the baking basket, shown in an open configuration;

FIG. 3 is a front view of the baking basket in FIG. 1;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict portions of the baking basket that form no part of the claimed design.

1 Claim, 8 Drawing Sheets
